(57) **CLAIM**

The ornamental design for a foundation container as shown and described.

DESCRIPTION

FIG. 1 is a front, right, top perspective view of a foundation container showing the new design.

FIG. 2 is a rear, left, top perspective view of the foundation container of FIG. 1.

FIG. 3 is a front elevation view of the foundation container of FIG. 1.

FIG. 4 is a rear elevation view of the foundation container of FIG. 1.

FIG. 5 is a left side elevation view of the foundation container of FIG. 1.

FIG. 6 is a right side elevation view of the foundation container of FIG. 1.

FIG. 7 is a top plan view of the foundation container of FIG. 1.

FIG. 8 is a bottom plan view of the foundation container of FIG. 1.

FIG. 9 is a front, right, top perspective view of the foundation container of FIG. 1 with the cap removed and the inner bottle partially elevated; and,

FIG. 10 is a front, right, top perspective view of the foundation container of FIG. 1 with the cap removed and the inner bottle removed. The rear, left, top perspective view of the uncapped foundation container is identical to the front, right, top view of the uncapped foundation container shown in FIG. 10. The rear, left, top perspective view of the inner bottle of the foundation container is identical to the front, right, top perspective view of the inner bottle of the foundation container shown in FIG. 10, except that the dispensing nozzle shown on the front of the inner bottle of the foundation container in FIG. 10 is not present on the rear of the inner bottle of the foundation container.

The bottom surface of the inner bottle of the foundation container is flat and devoid of ornamental features.

(Continued)

The broken lines depict portions of the foundation container that form no part of the claim.
